UNITED STATES PATENT OFFICE.

BENJAMIN AGEE BOWLES, OF WASHINGTON, DISTRICT OF COLUMBIA.

WINDOW GUARD.

Application filed February 11, 1926. Serial No. 87,650.

This invention relates to improvements in window guards, having for an object to provide the usual lower sliding sash of a building window with a novel and effectual form of guard whereby with moving of the equipped sash to an open or partially open position, said guard will be moved into a position to cover or span the resultant opening and hence, prevent the effecting of entry 10 into the building therethrough.

Another and equally important object of the invention is to provide a guard of the character mentioned wherein the same is positively secured to the lower portion of 15 the window sash and is of such construction as to simulate the appearance or design of the sash in order that the general appearance of the window will be in no way altered or detracted from with movement of 20 the guard into an exposed position, as with usage of ordinary bars and gratings or similar guard devices, thus affording a device especially advantageous for private dwellings and like structures wherein the appearance 25 of guard bars or their equivalents are more or less repulsive to the æsthetic emotions.

It is also an object of the invention to provide a guard in connection with which screens may be conveniently used so as to 30 close the window opening, with arrangement of the guard in operative position, to the passage of insects therethrough during certain seasons, such screens being readily removable from the guard when not desired.

Other objects of the invention will be in part obvious and in part pointed out hereinafter.

In order that the invention and its mode of operation may be readily understood by 40 persons skilled in the art, I have in the accompanying illustrative drawings, and in the detailed following description based thereupon, set out one possible embodiment of the same.

In these drawings:

Figure 1 is a front elevation of a window wherein the lower sliding sash thereof is equipped with the improved guard,

Figure 2 is a vertical transverse section 50 through the same,

Figure 3 is an enlarged fragmentary detail in elevation showing the novel form of sash and guard,

Figure 4 is a fragmentary detail in vertical transverse section showing the manner 55 in which screens are adapted to be arranged

in the openings provided between the bars of the guard, and

Figure 5 is a fragmentary detail in elevation showing one of the screens engaged 60 with the guard.

Having more particular reference to the drawing, in connection with which like characters of reference will designate corresponding parts throughout, I have shown 65 for purposes of illustration herein my improved window guard as being used in connection with the standard form or design of vertically slidable window sash 1, said sash being slidably received in a suitable 70 window frame 2 and adapted to normally close the lower portion thereof as is indicated in the Figure 1; an upper slidable sash 3 being arranged in another guide way 75 provided therefor in the said frame 2, as is usual in the art. The window frame 2 is provided with a sill portion 4 and this sill portion has a longitudinally disposed opening or way formed therein adapted to receive the improved form of guard therein 80 and therethrough at times. Also, it is to be noted in this connection that a pocket or chamber is formed in the building wall receiving the window frame 2 directly below 85 the opening 4 in the window frame sill, as is indicated at 5 and, as shown in the Figure 2, this chamber 5 is adapted to receive the window guard designated at this time in its entirety by the numeral 6, when said guard is in an inoperative position, as when 90 the sash 1 has been moved to its lowermost or closed position with respect to the lower portion of the window frame 2. If desired, a drain opening or drain openings 7 may be 95 formed in the lower portion of the building wall communicating with the bottom of the pocket 5 whereby to permit of draining of water therefrom and by consequence, to prevent premature deterioration of the adjacent wood work or other material.

As will be noted, the window sash 1 is of the usual divided pane design, having a plurality of relatively right angularly disposed parallel bars or lintels generally indicated by the numeral 8 supported upon the superstructure thereof and adapted to receive and support transparent or translucent panes 9 therein in the usual manner.

The opposite sides of the window sash 1 are extended for distances below the lower side portion thereof indicated by the numeral 10, such extensions being arranged

parallel to said sides of the sash 1 from which they are extended and having a cross bar 11 fixedly supported therebetween adjacent their free or lower extremities; such 5 extensions being designated at this time for the purpose of convenience by the numeral 12. By reason of the arrangement or formation of these extensions 12 and the cross bar 11 engaged between the free and lower extremities thereof, it will be seen, upon reference to the Figure 1, that a frame corresponding in general configuration and size to the sash 1 will be provided. In order 10 that this frame constituted by the bar 11 and the extensions 12 will further simulate the appearance of the lower sliding sash 1, I divide the same into a plurality of squared openings by the arrangement of a plurality of relatively right angularly disposed intersecting bars or lintels generally indicated herein by the numeral 13. The construction and formation of the last mentioned bars 13 corresponds identically with that of the aforesaid bars or lintels 8 and 15 by consequence, it will be understood that a replica of the lower sliding window sash 1 will be provided by this arrangement. However, the squared openings provided by the arrangement of the bars 13 are normally 20 left open to permit of ventilation.

During certain seasons, it becomes desirable that the open spaces provided in the guard 6 shall be closed as against the passage of insects therethrough and to accomplish this, I preferably employ a plurality 25 of screens, comprising substantially square frames 14 of a size and shape to be snugly received in the aforesaid squared openings provided by the bars 13; portions of the said bars 13 being provided with cross sectionally right angularly formed seats designated by the numeral 15 adapted to snugly receive said screen frames 14 therein. The frames 14 in turn, are covered by a suitable 30 foraminated material, such as wire or metal screen designated by the numeral 16. Thus, it will be readily understood that with arrangement of the various screen frames 14 in the squared openings formed in the guard 35 6, said guard will be fully protected against the passage of insects thereby into an equipped building. If desired, each of the screen frames 14 may be provided with suitable means for securing the same in engagement with the adjacent portions of the right angularly disposed bars 13 receiving them and to this end, I have shown herein, said screens as being equipped with inwardly disposed spring metal finger actuated catches 40 generally indicated by the numeral 17, the inner portions of which catches are adapted to have overlapping engagement with adjacent portions of the bars 13 as is clearly 45 shown in the Figure 4. Thus, it will be understood that with engagement of the

spring catches 17 with adjacent portions of the bars 13, accidental or undue displacement of the frames 14 will be avoided. Yet, when desired, the screen may be readily removed from the square openings in the window guard 6 merely by disengaging the catches 17 from the adjacent portions of said bars 13 and then forcing the frames 14 outwardly from the guard 6.

From the foregoing, it will be understood 75 that I have provided a novel yet exceedingly simple form of window guard which because of its construction will be found particularly advantageous and desirable for use in private dwellings wherein some form of 80 guard is oftentimes required or desired for closing a window opening upon raising of the window sash against undesired entry. In my invention, it will be understood that with raising of the lower sliding sash 1 to 85 its open or partially open position, the guard 6 comprehended by the extensions 12 and the cross bar 11 will be moved upwardly to fully cover the resultant opening and thereby, prevent the effecting of entry into 90 the equipped building therethrough. At the same time, it will be appreciated that because of the fact that the guard 6 simulates the general appearance and design of the sliding sash 1, said guard when exposed or 95 partially exposed will in no way detract from the appearance of the equipped window nor will it in any way become repulsive to the aesthetic emotions. When the window sash 1 is moved to its lowermost position, 100 the guard 6 will be caused to move downwardly into the receiving pocket 5 provided therefor in the building wall and by consequence, will become concealed from view and thus, will in no way alter the appearance 105 of the usual sash or window construction.

Manifestly, the construction shown is capable of considerable modification, and such modification as is within the scope of my 110 claims, I consider within the spirit of my invention.

I claim:

1. A slidable window sash having the opposite sides extended for distances beyond 115 one end thereof, a cross bar connected between the free ends of said extensions, and a plurality of bars carried between said extensions and said cross bar and the lower portion of said sash.

2. A slidable window sash having a guard connected to and movable with the lower portion thereof, said guard being constructed in a manner to simulate the appearance of the sash, and a plurality of screens adapted to be removably supported upon said guard.

3. In combination with a slidable window sash having a plurality of relatively right angularly disposed bars thereon, di- 130

viding it into a plurality of substantially square pane receiving openings, the opposite sides of said sash being extended beyond one end thereof, a bar secured between 5 the free extremities of said extensions, a plurality of relatively right angularly disposed bars supported between said extension and said bar and the lower portion of said sash, said last mentioned bars simulating 10 the appearance and formation of said first mentioned bars, and a plurality of screens receivable upon portions of said last mentioned bars.

comprising a main frame divided transversely and intermediately of itself into a pair of complemental subordinate frames, a plurality of relatively spaced transversely and longitudinally disposed bars fixedly carried by each of said subordinate frames, 20 the bars of one of said subordinate frames being adapted to fixedly receive panes therein, and screen carrying frames removably receivable in the spaces between the bars of the remaining subordinate frame. 25

In witness whereof I have hereunto set my hand.

BENJAMIN AGEE BOWLES.

4. A device of the character described
